In Great Britain December 31, 1934

12 Claims. (Cl. 122—459)

This invention relates to steam generating and superheating installations, and has particular reference to a method of and means for protecting the superheater elements of such installations during the periods of raising steam pressure in the respective boilers.

It will be realized that it is important to maintain superheater elements at all times at a safe temperature, whether the superheaters be of the convection or radiant type, and in some installations provisions are made for flooding the superheaters during pressure raising. Instead of flooding, however, protection can be afforded to steam superheaters during these periods by circulating steam through them. Frequently, during these periods of pressure raising, steam is passed from the boiler through the superheater elements to prevent the latter being overheated, the steam after flowing through the superheater being discharged to waste through the drains or blow-downs of the superheater. Thus there is waste of pure or treated water and of heat, and it follows that where large boilers are concerned the cost of the water and heat so wasted amounts to a relatively large sum.

Of the methods which have been proposed of protecting steam superheaters in boilers during pressure raising periods probably the most efficient is flooding, assuming the means to effect this to be properly designed, but, nevertheless, flooding is objectionable in certain respects, as is well known to those engaged in the art. Amongst the other methods of protection which have been proposed is one which, although using steam as the cooling medium, seeks to eliminate or minimize the waste of pure water and heat above mentioned.

According to such known method a saturated steam range is provided in the boiler house with valve controlled connections to the various superheaters, whereby the superheater of a boiler being brought up to pressure is isolated from said boiler and saturated steam from the saturated steam range is passed through it into the main superheater steam range of the boiler house. Another known method, which purports to eliminate waste of heat and water, consists in circulating steam generated in the boiler during pressure raising through the superheater to cool the elements of the latter, and passing such steam to a feed water heater where the heat is transferred from the steam to the feed water, the steam condensed, and the condensate returned to the feed system.

The present invention seeks to provide an im-

proved, simple, cheap and efficient method of, and means for, protecting a steam superheater of a boiler from overheating during the firing up or pressure raising period, which, while being such as to avoid heat and water losses, shall be such as to necessitate the consumption of a minimum of power from a source other than the said boiler.

It also is an object of the invention to provide a method of, and means for, protecting a steam superheater of a boiler from overheating during pressure raising which shall avoid the use of additional large stop valves, and shall employ apparatus occupying very little space; further, the additional piping required need be of relatively small diameter only, and this fact will assist materially in obtaining an efficient apparatus at relatively low cost.

According to this invention the superheater of a boiler is protected against overheating during pressure raising in the boiler by flowing through the superheater steam generated in the boiler, and, by means of an appropriate apparatus included in a local circuit, returning said steam to the said boiler, there being delivered to said apparatus, and thence into the boiler, aqueous fluid under a pressure above that obtaining in the boiler, which fluid in flowing through said apparatus induces the flow of steam through the superheater and on leaving said apparatus carries the said steam with it into the boiler.

The apparatus which by means of aqueous fluid under pressure flowing through it induces the steam flow through the superheater and returns it to the boiler, and which may be termed an energy converter, comprises a chamber connected to the outlet header of the superheater to receive steam therefrom, and a converging nozzle in said chamber from which nozzle the said aqueous fluid is directed into a diverging tube, the inlet of which is connected to said chamber. The aqueous fluid may be either steam or water and is at a pressure above that obtaining in the boiler with which the superheater and energy converter are associated, so that it is able to enter the boiler against the boiler pressure.

Where the aqueous fluid employed as the power medium in the energy converter is steam, such steam preferably would be saturated steam from another boiler, or from the saturated steam range of the boiler house if such range be provided, but it may be steam from the boiler in which pressure is being raised, the pressure of the steam in this case being increased to the necessary extent by an appropriately driven pump. Should the

aqueous fluid be water, it may be taken from the water space of the boiler with which the superheater under protection is associated or from the feed range of the boiler house. In the former case, the water may be placed under the necessary pressure by a pump driven by any appropriate motive means, as for example an electric motor, and in the latter case the pressure of the feed water, if necessary, may be increased by a pump.

In order that the manner in which the invention may be put into practice may be better appreciated, certain embodiments of the invention, selected as examples, will now be described with reference to the accompanying drawing, in which—

Fig. 1 shows diagrammatically portions of two boiler and superheater units of an installation equipped with superheater protection or steam circulating means according to one embodiment of the invention, the power medium employed in the energy converting apparatus of the steam circulating means of a unit being saturated steam drawn from another boiler or boilers of the installation.

Fig. 2 illustrates diagrammatically another embodiment of the invention in which steam which has passed through the superheater of a boiler or unit has its pressure increased and is employed as the power medium in the energy converting apparatus of the steam circulating means of the unit.

Fig. 3 illustrates diagrammatically a further embodiment of the invention in which water from the boiler is employed as the power medium of the energy converting apparatus of the steam circulating means of the unit, and

Fig. 4 shows more or less diagrammatically the construction of the energy converting apparatus employed in steam circulating means according to the invention.

Referring firstly to Fig. 1, the two units of the installation there shown are marked A and B respectively, a portion only of the unit B being illustrated. Each unit comprises a boiler, a steam and water drum 1 of which is shown, and a superheater comprising elements 2 and inlet and outlet headers 3 and 4 respectively. The steam space of the drum 1 is connected by a pipe 5 to the inlet header 3 of the superheater and by a branch 6 controlled by a stop valve 7 to a saturated steam range or ring main 8. The outlet header 4 of the superheater is connected as usual by a pipe 9 controlled by a stop valve 10 to the superheated stream range of the installation which is not shown in the drawing. 11 indicates an energy converting apparatus, which will be described later, the general construction of which is shown in Fig. 4, and which 60 comprises a steam chamber 12 connected by a pipe 13 equipped with a stop valve 14 to the pipe 9 receiving superheated steam from the header 4. A check valve 15 may be interposed between the chamber 12 and the stop valve 14. Entered in the steam chamber 12 of the energy converter is the outlet end portion of a converging tube or nozzle 16, the inlet end or larger end of the nozzle being connected by a pipe 17 equipped with an appropriate control valve 18 to the saturated steam range or ring main 8. Axially aligned with the converging nozzle 16 is a diverging tube 19, this tube being bell-mouthed or flared at its entrance more or less as shown at 19a in Fig. 4. The flared entry end of the diverging tube 19 is shown spaced from the out-

let end of the nozzle 16 to provide for open communication between such inlet end of the tube 19 and the steam space or chamber 12 of the energy converter; the relative dispositions of the outlet end of the nozzle 16 and the inlet end 5 of the tube 19 may vary provided the arrangement is such that the nozzle 16 delivers into the throat of the tube 19 and said throat is in open communication with the chamber 12. The outlet or delivery end of the diverging tube 19 is connected by a pipe 20 to the boiler drum 1 such pipe 20 preferably discharging into the drum below the water level therein. The return line or pipe 20 would be equipped with a check valve 21 to prevent water from the drum flowing into 15 the energy converter when the boiler is on load and the energy converter idle. A stop valve may also be provided if desired.

Assuming that pressure is being raised in the unit A and that the unit B is on load, the valves 7 and 10 of unit A will be closed and the valve 14 of unit A and valve 7 of unit B will be open as also will be the valve 18 of unit A. Saturated steam delivered by the boiler of unit B into range 8 will flow by way of pipe 17 and valve 18 into 25 the energy converter 11 of unit A. It will be appreciated that such saturated steam is at relatively high pressure and the pressure energy of such steam is converted in the nozzle 16 to velocity energy. The steam enters the throat of 30 the diverging tube 19 at high velocity and at a pressure less than that in boiler drum 1 and induces a flow of steam through the superheater into chamber 12 of the energy converter. The divergent tube 19 converts the velocity energy of 35 the high velocity steam from the nozzle 16 into pressure energy, and raises its pressure above that existing in the boiler drum 1 of boiler A. The steam delivered by the divergent tube 19 into the pipe 20 discharges into the boiler, preferably below the water level therein as already mentioned. This steam comprises the saturated steam supplied to the energy converter and the steam which has flowed through the superheater 2 and has performed protective duty therein. 45 Thus, according to the invention, the steam from the boiler of a unit is utilized to protect the superheater of the unit during pressure raising and is returned to the said boiler. The steam which has flowed through the superheater 2 is at relatively high temperature and by delivering it into 50 the water space of the boiler, together with the relatively small quantity of saturated steam used in the energy converter, the raising of pressure in the boiler will be accelerated.

Referring now to Fig. 2, in the embodiment of the invention therein illustrated, instead of supplying to the converging nozzle 16 of the energy converter saturated steam from another unit of the installation, a relatively small percentage 60 (for instance, 10%) of steam which has passed through the superheater 2 is taken from the pipe 13 through a branch 22, by a steam pump 23 driven by any appropriate motive power, as for its example, by an electric motor. The pump 65 23 raises the steam it draws from the pipe 13 to a relatively high pressure and delivers it by a pipe 17a, to the energy converter 11, where it operates to create a pressure drop across the superheater 2 and to return circulated steam to 70 the boiler drum 1 in the manner already described with reference to the embodiment of the invention illustrated in Fig. 1. Further description of this embodiment of the invention is not considered necessary, but it may be men- 75

tioned that the arrangement according to Fig. 2 is such that it may be applied to an independent boiler and superheater unit or to respective units comprised in an installation. It will also be appreciated that only a small amount of power is required to operate the pump 23 in order to raise the relatively small quantity of steam to the high pressure needed to render the energy converter operative to insure an efficient circulation of steam through the superheater.

In the embodiment of the invention shown in Fig. 3, instead of steam being employed as the power medium in the energy converter, water at high pressure is supplied to said energy converter. As shown in Fig. 3, a water line 24 is taken from the water space of the boiler drum 1 to the inlet of the converging nozzle of the energy converter 11 and a pump 25 is included in the water line 24, a check valve 26 being interposed between the pump and the boiler. The pump 25 is driven by a small electric motor or other appropriate motive means. As in the embodiments of the invention shown in Figs. 1 and 2, the energy converter discharges through a return line 20 into the water space of the drum 1. In the embodiment of the invention under description, it will be appreciated that steam which has passed through the superheater 2 and is drawn through pipe 13 into the steam chamber 25 of the energy converter by the high pressure water delivered into the divergent tube of the energy converter will be returned into the boiler with the said water by way of the pipe 20. If desired, instead of drawing the small quantity 35 of water for the energy converter from the boiler drum 1, it may be drawn from the feed line of the boiler. It will be appreciated that a boiler and superheater with steam circulating means according to Fig. 3, constitutes a self-contained 40 unit, in that steam from another boiler is not required to render the circulating means operative as in the case of the embodiment of the invention shown in Fig. 1, and the circulating means according to Fig. 3, therefore, may be 45 applied to a single isolated boiler and superheater equally as well as to one of a number of boilers with superheaters in a boiler house.

If desired, means may be provided to regulate the flow through the energy converter of the aqueous fluid (steam or water) used as the power medium therein, in order to produce the required flow of steam through the superheater to be cooled over the range of boiler pressure from atmosphere to main range pressure. For example, means may be provided for maintaining a difference of constant or other predetermined value between the pressure in the boiler and that at the entrance to the energy converter for circulating steam, by automatically regulating the opening of the valve 18 in Fig. 1 or automatically regulating the operation of the pumps 23, 25, Figs. 2 and 3, to thereby control the pressure of aqueous fluid supplied to the converging nozzle 16 of the energy converting apparatus, according to the pressure obtaining in the boiler of the unit in which pressure is being raised. For example, as shown in Fig. 1, a pressure line 30 is connected to the steam drum 1 and to a bellows 31 or other suitable apparatus adapted to regulate the opening of valve 18 in accordance with the pressure existing in the boiler. The steam pump 23 in Fig. 2 and the water pump 25 in Fig. 3 are likewise associated with devices 31 responsive to steam pressure for regulating their speed of operation.

The apparatus according to the present invention is small and cheap, and is such that a relatively large quantity of steam may be circulated through a superheater by means of a small quantity of high pressure steam or water, whereby effective cooling of the superheater will be obtained with a small consumption of power from a source other than the boiler with which such superheater is associated.

What I claim is:

1. The method of protecting a steam superheater of a boiler from overheating during pressure raising, which consists in flowing through the superheater and returning to the boiler steam generated in the boiler, the flow of steam from 15 and its return to the boiler being effected by flowing into the boiler through an appropriate apparatus connected to the superheater outlet and to the boiler aqueous fluid supplied to such apparatus at a pressure higher than the then 20 existing boiler pressure, the aqueous fluid in flowing through such apparatus inducing the flow of steam through the superheater and thereafter carrying such steam with it into the boiler.

2. The method of protecting a steam superheater of a boiler from overheating during pressure raising, which consists in supplying to an energy converting apparatus aqueous fluid at a pressure above that obtaining in the boiler, changing in said apparatus the pressure energy 30 of the aqueous fluid to velocity energy, utilizing the high velocity fluid so produced to induce a flow of steam from the boiler through the superheater thereof to said apparatus, reconverting in said apparatus the velocity energy of the aqueous fluid to pressure energy to restore said fluid to a pressure above that obtaining in the boiler, and delivering into the boiler said aqueous fluid together with the steam from the superheater carried forwardly from said apparatus by said 40 fluid.

3. The method of protecting a steam superheater of a boiler from overheating during pressure raising as claimed in claim 2, characterized in that the aqueous fluid under pressure 45 supplied to the energy converter is saturated steam from another boiler or boilers on load.

4. In a steam generating and superheating installation, the combination with a boiler and its superheater, of means for inducing a flow of 50 steam from the boiler through the superheater during pressure raising and returning such steam to the boiler comprising an energy converting apparatus having a steam chamber connected by a conduit to the outlet from the superheater 55 so as to receive steam therefrom, a converging nozzle in said chamber to the entry end of which nozzle is supplied aqueous fluid at a pressure above the boiler pressure, and a diverging tube axially aligned with said nozzle and having its 60 inlet end bell-mouthed and open to said chamber and into which end of said tube said aqueous fluid is directed by said nozzle, a duct connecting the delivery end of said diverging tube to the boiler, check valves in said conduit and duct respectively to prevent fluid flow in the reverse direction therethrough when the boiler is on load, and means for regulating the pressure of the aqueous fluid supplied to the energy converter to maintain constant the difference between the pressure in the boiler and that at the entrance for steam from the superheater to the 70 said chamber.

5. A steam generating and superheating installation comprising a plurality of boiler and 75

superheater units each equipped with means for protecting its superheater during pressure raising in its boiler as claimed in claim 4, wherein the steam space of each boiler is connected 5 through a stop valve to a saturated steam line and the entry end of the converging nozzle of the energy converter is connected to said line through a pressure regulating valve to receive saturated steam therefrom at an appropriate pressure.

10. 6. A steam generating and superheating installation as claimed in claim 4, wherein a branch from the conduit leading steam from the superheater to the steam chamber of the energy converter is connected to the intake of a steam pump 15 driven by an electric motor or other appropriate motive means, and the delivery of said pump is connected to the entry end of the converging nozzle of said energy converter, whereby there is supplied to the said nozzle, as the aqueous 20 fluid under pressure, steam which has passed through the superheater.

7. A steam generating and superheating installation as claimed in claim 4, wherein a local water line connects the water space of the boiler 25 with the entry end of the converging nozzle of the energy converter and a pump is provided in said line to raise the pressure of the water above the boiler pressure, a check valve being interposed in said line between the boiler and the 30 pump.

8. The method of protecting a steam superheater of a boiler from overheating during pressure raising which consists in drawing water from the boiler, supplying said water to an energy 35 converting apparatus at a pressure above that existing in the boiler, changing in said apparatus the pressure energy of said water to velocity energy, utilizing the high velocity water so produced to induce a flow of steam from the boiler 40 through the superheater thereof to said apparatus, reconverting in said apparatus the velocity energy of said water to pressure energy to restore said water to a pressure above that existing in the boiler, and delivering into the 45 boiler said water together with the steam from the superheater carried forwardly from said apparatus thereby.

9. In the method of protecting a steam super-

heater from overheating during pressure raising as claimed in claim 2, wherein the aqueous fluid under pressure supplied to the energy converter is steam generated in the boiler, the step of increasing the pressure of said steam before supplying it to said energy converter. 5

10. In a boiler having a steam and water drum and a superheater connected to receive steam therefrom; a conduit connecting the outlet end of the superheater with said drum; an energy 10 converter so placed in said conduit as to induce a flow of steam generated in the boiler through said superheater to protect the latter when pressure is being raised in said boiler; and means for supplying steam generated in the boiler to 15 said converter at a pressure higher than exists in said boiler for actuating the latter to induce said flow of steam through the superheater and return it to said drum.

11. In a boiler having a steam and water drum 20 and a superheater connected to receive steam therefrom; a conduit connecting the outlet end of the superheater with said drum; an energy converter so placed in said conduit as to induce a flow of steam generated in the boiler through 25 said superheater to protect the latter when pressure is being raised in said boiler; and means for supplying water to said converter at a pressure higher than exists in the boiler for actuating said converter to induce said steam flow 30 through said superheater and return said steam and water to said drum.

12. In a boiler having a steam and water drum and a superheater connected to receive steam therefrom; a conduit connecting the outlet end 35 of the superheater with said drum; an energy converter so placed in said conduit as to induce a flow of steam generated in the boiler through said superheater to protect the latter when pressure is being raised in said boiler; a conduit and 40 pump therein for withdrawing water from said drum and supplying it to said converter at a pressure lighter than exists in said boiler for actuating said converter to induce said steam flow through said superheater and return said 45 steam and water to said drum.

JOHN EDWIN WOOD.
